OVERALL BUCKLE

Edward F. Pavek, Stillwater, Minn.

Application August 25, 1941, Serial No. 408,205

7 Claims.

(Cl. 24—248)

My invention relates to an improvement in overall buckles, wherein it is desired to provide a buckle which will permit overall straps to be easily adjusted and which are easily detachable when the garments are washed.

In overalls it is usual practice to provide buckles which may be used to shorten or lengthen the supporting straps. These buckles permit the adjustment of the straps. However, with the usual form of buckle the straps must be threaded through the same, which requires considerable time for the manufacturer. Furthermore because of the fact that the usual adjustment buckles are difficult to remove they are often left on the straps when the garments are washed and often become injured when the garments are wrung dry. The fact that the adjustment buckles are somewhat difficult to operate also requires considerable time for the salesman who sells the overalls, as he must make adjustments while fitting the overalls to the wearer.

It is the object of the present invention to provide an overall buckle which will clamp the overall straps in any desired adjustment and which may be removed by a simple action. Accordingly when it is desired to change the adjustment of the overall straps, the straps are folded to the desired adjustment and the buckle again snapped to clamp the straps in this adjusted position.

A feature of my invention relates to the simple adjustability of the snap, which permits the removal of the snaps and the button engaging loops which might otherwise be injured in the washing or drying process.

A further feature of the present invention resides in the provision of a loop of wire, or the like, which overlies one surface of the straps, and a flat spring clamping member which engages against the opposite surfaces of the straps to clamp the straps between the loop and the spring strip. The spring strip is pivotal with respect to the loop and engages the loop under spring tension to the end thereof opposite the pivotal attachment. By merely springing the end of the spring strip free from the end of the loop, the buckle may be disconnected.

A further feature of the present invention resides in the embossing of a name or any desired advertising matter on the spring strip in such a manner that the inner surface of the spring strip presents an irregular surface to bear against the straps to prevent slippage of the straps through the buckle.

A further feature of the present invention resides in the provision of a pocket or recess in the end of the spring strip, into which may engage a projection on the end of the loop so as to lock the spring strip and loop in closed position.

These and other objects and novel features of my invention will be more clearly and fully set forth in the following specification and claims.

In the drawing forming a part of my specification:

Figure 1 is a perspective view of a portion of a pair of overalls showing the adjustment loops in place thereupon.

Figure 2 is an elevation view of the buckle removed from the straps.

Figure 3 is a top plan view of the buckle shown in Figure 2.

Figure 4 is a front elevation view of the buckle in position upon an overall strap.

Figure 5 is a rear view of the buckle in place upon an overall strap.

Figure 6 is a sectional view through the buckle, the position of the section being indicated by the line 6—6 of Figure 2.

Figure 7 is a sectional view vertically through the buckle and strap, the position of the section being indicated by the line 7—7 of Figure 4.

Figure 8 is an elevation view of a modified form of construction.

The overalls A may be of any desired or preferred type, usually provided with a bib 10, to which is attached a pair of buttons 11. The buttons 11 are designed for engagement by button engaging loops 12 which are held within a fold provided by doubling the ends of the supporting straps 13.

The straps 13 are doubled through the buckles 12 and the free end 14 of the strap 13 is folded to the rear of the body of the strap, as indicated in Figure 7 of the drawing. The buckles B hold the strap in folded relation and may be released in a simple manner to change the adjustment of the straps 13.

Each buckle B includes a loop 15 which includes a pair of transversely extending substantially parallel bars 16 and 17, and a pair of substantially parallel loop ends 19 and 20. Connecting the transverse bars 16 and 17 and the loop ends 19 and 20, I provide outwardly bowed arcuated portions 21 which permit free movement of the straps and free pivoting of the two parts of the buckles.

Pivoted to the loop end 20, I provide a spring plate 22. The spring plate 22 is bent to form a substantially cylindrical barrel or journal 23 encircling the loop end 20 and to provide pivotal attachment between the spring plate 22 and the loop 15. At the opposite end or free end of the spring plate 22, I provide an arcuated channel member 24 designed to engage about the loop end 19 with spring tension. A lip 25 at the extreme end of the plate 22 forms a means whereby the spring plate may be engaged by a finger and unsnapped from the loop end 19. The channel shape of the plate member 24 closely encircles

the loop end 19 and holds the clamping plate 22 in locked relation to the loop 15.

On the rear surface of the loop 15, I provide a series of projections or irregularities 26 which engage against the strap 13 to prevent the strap from sliding through or past the loop 15. In order to hold the plate 22 from slipping with respect to the strap 13, I provide in preferred form, an embossed name or symbol indicated in the drawing by the numeral 27 in which the letters project inwardly toward the loop 15 and engage against the surface of the strap 13 to prevent slipping of the strap.

In order to more securely lock the plate 22 in clamping position, I provide a recess 29 in the channel end 14 of the strip 22, and in the end 19 of the loop 15 I provide an outward projection or lug 30 designed to extend into the pocket or recess 29. This outward projection 30, when engaged in the recess 29, locks the plate 22 from pivotal movement with respect to the loop 15.

In the operation of the buckle B, the strap 13 is folded to include the button engaging loop 12 and the free end 14 of the strap 13 is folded up against the inner surface of the strap 13. The clamp B is then applied in place with the loop 15 overlying the outer surface of the strap and the plate 22 underlying the inner surface of the strap. The two parts of the buckle B are then clamped together by pressing the end 19 of the loop 15 into the channel-shaped end 24 of the spring plate 22, the outward projection 30 engaging in the recess 29. When locked in this position, the strap 13 is securely clamped between the two parts of the clamping device and held from slipping by the inward projections 26 on the loop 15 and the forward projections 27 on the plate 22.

In the modified form of construction illustrated in Figure 8 of the drawing, the operation is similar to that previously described in conjunction with the buckle B. I have found that the overall straps 13 are sometimes formed with turned hemmed edges, making the edges of the strap much thicker than the center portion of the strap. With these thickened straps, it is impractical to use the buckle B without using a relatively narrow strip 22. For overall straps which are provided with turned marginal edges, so as to provide thickened longitudinal strap edges, I form the buckle C, illustrated in Figure 8 of the drawing.

The buckle C is formed with a loop 31 which is identical in form and shape to the loop 15. A strip 32 is provided with a journal 33, similar to the journal 23 and which encircles one end 34 of the loop 31. The other end of the strip 32 is provided with a channel 35 which engages over the end 36 of the loop 31. A recess 37 is formed in the channel end 35 to accommodate a projecting lug 39 on the end 36 of the loop 31. A name, such as 40, may be embossed into the strip 32.

Notches 41 are provided in the end of the strip adjacent the journal 33 and notches 42 are provided in the strip 32 adjacent the channel end 35. As a result, the thickened edges of the overall straps may engage in these notches without decreasing the force which the spring strip 32 has upon the center portion of the overall strap. Thus lip portions 43 are provided on the spring strip 32 between the notches 41 and the notches 42 to engage against the strap under spring tension.

In accordance with the patent statutes, I have

described the principles of construction and operation of my buckle, and while I have endeavored to set forth the best embodiment thereof, I desire to have it understood that this is only illustrative of a means of carrying out my invention and that obvious changes may be made within the scope of the following claims without departing from the spirit of my invention.

I claim:

1. An overall buckle comprising an elongated loop having substantially parallel sides and ends, outwardly bowed arcuations in said sides connecting said sides to said ends, a spring plate pivotally secured to one end of said loop, a curved end on the opposite end of said plate designed to engage the other end of said loop under spring tension.

2. An overall buckle comprising an elongated loop having substantially parallel sides and ends, outwardly bowed arcuations in said sides connecting said sides to said ends, a resilient plate pivotally secured at one end to one end of said loop, and channel means at the other end of said plate frictionally engageable with the other end of said loop.

3. An overall buckle comprising an elongated loop, substantially parallel ends thereupon, a spring plate pivotally secured to one of said ends and engageable with the other of said ends under spring tension, and lettering embossed into the rear surface of said spring plate to provide a roughened forward surface comprising rounded projections on said spring plate to engage the strap being clamped between said loop and said plate.

4. An overall buckle comprising an elongated loop having substantially parallel ends thereupon, a spring clamping plate having a journal at one end to pivotally engage one of said ends of said loop, a spring flange on the other end of said plate engageable under spring tension against the other end of said loop, an irregular surface on said loop to engage against one surface of the strap clamped between said loop and said plate, and means embossed into said plate to provide a roughened forward surface to engage against the opposite side of the strap clamped between said plate and said loop.

5. An overall buckle for overall straps comprising an elongated loop, a spring plate pivotally secured at one end to one end of said loop, a curved engaging flange at the other end of said plate engageable with the other end of said loop, and notches in said spring plate adjacent each end thereof to compensate for thickened strap edges to be clamped by said buckle.

6. A buckle comprising an elongated loop having substantially parallel sides and ends, outwardly bowed arcuations in said sides connecting said sides to said ends, a plate pivotally secured at one end to one end of said loop, and means at the other end of said plate engageable with the other end of said loop.

7. A buckle comprising an elongated loop, a spring plate continuously curved between its ends pivotally secured at one end to one end of said loop, a curved engaging member at the other end of said plate resiliently engageable with the other end of said loop, a projection in said other end of said loop projecting longitudinally beyond the end of said loop, and a recess in said curved end of said engaging member, said projection being engageable in said recess, said plate being substantially narrower than said loop.
